UNITED STATES PATENT OFFICE.

JOHN SMITH AND FERDINAND STEINKE, OF HORICON, WISCONSIN.

CULTIVATOR.

SPECIFICATION forming part of Letters Patent No. 251,961, dated January 3, 1882.

Application filed October 24, 1881. (No model.)

To all whom it may concern:

Be it known that we, JOHN SMITH and FERDINAND STEINKE, of Horicon, in the county of Dodge and State of Wisconsin, have invented certain Improvements in Cultivators, of which the following is a specification.

Our invention relates to a friction device for holding cultivator teeth or shovels in an operative position until subjected to an excessive strain, and then permitting them to yield and swing back to prevent breakage or injury.

The invention consists in an annulus or band formed upon or secured to the shovel-standard, arranged to encircle a stationary hub or boss secured to the beam or drag-bar, and provided with a tightening or clamping device, or attached to a stationary block and arranged to encircle a hub or boss formed on the shovel-standard.

The invention further consists in means hereinafter described for attaching the shovel or tooth to the standard.

In the accompanying drawings, Figure 1 represents a side elevation of our device in its preferred form, the beam or drag-bar broken away to show the parts; Fig. 2, a view of the parts separated one from another; Figs. 3, 4, 5, and 6, views showing slightly modified forms of the same.

The essential feature of this invention, so far as relates to the friction device, consists in the employment of a circular hub or boss and an encircling annulus or band provided with devices for tightening it upon the hub or boss, one of said parts being permanently fixed in position and the other arranged to move or swing about or upon the hub as a center of motion.

Referring to the drawings, A represents the shovel-standard; B, the beam or drag-bar by which it is carried; C, the hub or boss, and D the encircling band or annulus by which the necessary friction is produced.

In Fig. 1 the hub or boss C consists merely of a flat circular disk, and the annulus or encircling band D is formed directly upon and integral with the shovel-standard A. The annulus is passed about the disk or boss C, and the two are then passed upward into a slot, a, extending vertically through the beam or drag-bar B. When in proper position the disk or

boss is secured in place and held against rotation by two bolts, b, passing transversely through the disk and through the beam or drag-bar, as shown.

The annulus or band D is divided or open at one side and furnished with ears c, through which a clamping or binding bolt passes, the annulus being slightly smaller in its interior than the exterior of the disk, so that when the ears c are drawn together by the bolt the annulus or band is caused to bind upon the disk with any desired degree of friction, according to the extent to which the bolt is tightened.

The degree of friction is regulated, so that the standard and the shovel which it carries shall remain fixed or stationary in their working position until some obstruction is met with offering a resistance which would be sufficient to injure the shovel or standard or other part of the machine unless the standard be allowed to yield. When this point is reached the friction is overcome and the standard and shovel are permitted to swing back, the disk C serving as a pivot or center of motion.

In Figs. 3 and 4 a slightly-modified form of the annulus and boss or block is shown, by which a double friction-surface is obtained. In this instance the boss or block C, instead of being in the shape of a circular disk, is of the form represented in Figs. 3 and 4, having lateral perforated flanges e, by which to secure it to the beam or drag-bar, a segmental grooved portion, f, around which the annulus or band D passes, and an internal semicircular seat, g, to receive the circular head h of the standard A, which head serves as the pivot or center of motion upon which the standard swings. The friction-band or annulus C is in this case formed of a piece of metal rod or bar-iron bent around the segmental portion f, and having its ends passed through lugs or ears i, formed on the standard A, and held by nuts j, which serve also to produce the required degree of friction between the band D and its groove k and between the head h of the standard and its seat g.

Figs. 5 and 6 show another slight modification of the friction device, the hub or boss C being formed upon the standard A and the friction-band D being wound around the boss and having its ends passed through the flanges of a metal block or plate, E, which covers the

opening through which the standard is inserted into the beam or drag-bar, and also serves to strengthen the beam and afford a bearing for the hub or boss C, as shown in Fig. 6. 5 A stem, l, threaded and provided with a nut, m, extends outward through the side of the beam to retain the standard in place. In this as in the preceding form the friction of the band is increased or diminished by adjusting 10 the nuts n placed upon its ends. The standard is in each case formed with an enlargement or ears, o, near its lower end, through which are two slots or holes, p, from front to rear, and with lips or ears q near its upper end. Each 15 tooth or point F is made reversible, so that either a narrow point or a broad shovel may be brought into use by simply turning one or the other end down into a working position, the shank r of each tooth resting against the 20 front face of its standard, and the uppermost point of the tooth being passed between the lips or ears q, as shown. When in this position the shank is firmly secured by a metal strap or clasp, G, passing across the front and 25 around the sides of the shank r and through the holes or slots p.

The rear ends of the metal strap G are provided with inclined notches s, into or through which a pin or bolt, t, is passed, as shown, and 30 between the pin or the bolt and the rear face of the standard is inserted a wedge, u, by which the strap is drawn firmly against the shank of the shovel-point, and the latter is secured rigidly in position.

35 We are aware that friction devices adapted to hold shovel-standards at any desired angle and with any desired degree of firmness have been made in a variety of forms; but we are not aware that any one has hitherto provided 40 an encircling band capable of contraction upon a hub or boss to produce the desired amount of friction, one of said parts being fixed and the other movable relatively to each other.

We are also aware that straps and wedges

have been employed to secure shovel-points to 45 their standards, and we make no broad claim thereto.

Having thus described our invention, what we claim is—

1. The combination, in a cultivator, of a beam 50 or drag-bar, a shovel-standard, a hub or boss, and an encircling annulus or band adapted to be contracted upon the boss, the boss and annulus being attached, one to the beam and the other to the standard, substantially as and for 55 the purpose set forth.

2. In a friction device for cultivator-standards, the combination of a hub or boss and an encircling annulus or band provided with a 60 clamping device, substantially as shown, one of said parts being stationary relatively to the other.

3. The standard A, having at its upper end the annulus or band D, open at one side, and provided with a bolt, whereby it may be contracted, substantially as set forth. 65

4. The shovel-standard A, provided with lips q and openings or holes p, substantially as and for the purpose set forth.

5. In a cultivator, the combination of a shovel-standard, A, provided with slots or openings p and lips q, a shovel point or tooth, F, a strap or band, G, passing around the shank of the tooth and through the slots, and means, substantially as described, for tightening the strap 75 or band.

6. In combination with the standard A, provided with openings p, a shovel point or tooth, and a strap or band, G, adapted to straddle the tooth-shank and to pass through said openings, and notched as described, a pin or bolt, t, and wedge u, all combined and operating as 80 set forth.

JOHN SMITH.

FERDINAND STEINKE.
